(57) CLAIM

The ornamental design for a hidden shower storage, as shown and described.

DESCRIPTION

FIG. 1 is a perspective view of shower surround showing our new design;

FIG. 2 is a perspective view of the shower surround with the door closed thereof;

FIG. 3 is a top plan view thereof;

FIG. 4 is front view thereof;

FIG. 5 is an interior side view thereof; and,

FIG. 6 is another interior side view thereof.

The broken lines showing of a tub are for illustrative purposes and form no part of the claimed design.
